G. W. JONES.

INTERNAL COMBUSTION ENGINE.

APPLICATION FILED MAR. 12, 1915. RENEWED JAN. 18, 1918.

1,257,360.

Patented Feb. 26, 1918.

UNITED STATES PATENT OFFICE

GEORGE WASHINGTON JONES, OF CHICAGO, ILLINOIS.

INTERNAL-COMBUSTION ENGINE.

1,257,360.

Specification of Letters Patent. Patented Feb. 26, 1918.

Application filed March 12, 1915, Serial No. 13,834. Renewed January 18, 1918. Serial No. 212,537.

To all whom it may concern:

Be it known that I, GEORGE WASHINGTON JONES, a citizen of the United States, and a resident of Chicago, in the county of Cook and State of Illinois, have invented certain new and useful Improvements in Internal-Combustion Engines; and I do hereby declare that the following description of my said invention, taken in connection with the 10 accompanying sheet of drawing, forms a full, clear, and exact specification, which will enable others skilled in the art to which it appertains to make and use the same.

This invention has general reference to 15 internal combustion engines; in particular, to that type known as two cycle engines, and it consists, essentially, in the novel and peculiar combination of parts and details of construction, as hereinafter first fully set 20 forth and described and then set forth in the claims.

In the drawing already referred to, which serves to illustrate my said invention more 25 fully, Figure 1 is a vertical section of a two cycle engine embodying my invention, showing the working piston thereof at the beginning of its stroke; Fig. 2, a similar section showing the piston at approximately its lowest position; Fig. 3, a like section, 30 illustrating the piston in a position shortly after the beginning of the up or return stroke; Fig. 4, is a vertical section of the engine in line 4—4 of Fig. 1; Fig. 5, is a horizontal section in line 5—5 of Fig. 4. 35 Fig. 6, is an enlarged view of one of the scavenging piston parallel rods shown in section. Fig. 7, is a section of a fragment in line 7—7 of Fig. 5, on an enlarged scale. Fig. 8 is a fragment of one of the scaveng- 40 ing piston parallel rods shown in perspective.

Like parts are designated by correspond- 45 ing characters and symbols of reference in all the figures of the drawing.

The aim and object of my invention is the 50 production of a two cycle internal combustion engine in which the undesirable qualities common to that type of motor are eliminated, such as for instance, the necessity for a closed, tight crank case, to maintain what is known as "crank case compression," the liability of premature explosions, and the frequent mixing of the gases of combustion with the incoming charge.

In practising my invention, the foul or 55 exploded gases are forced out of the cylin-

der by means of a secondary scavenging piston located in the engine cylinder, above or behind the working piston therein, and which, when in its upper position, is directly adjacent the cylinder head of the motor, with but very little clearance between. Said secondary scavenging piston is at rest during approximately 135 degrees of the crank revolution on the downward stroke 60 of the working piston, at which point the said working piston has half uncovered the exhaust port in the cylinder. As the working piston passes the above mentioned point, the secondary piston is caused to rapidly descend to a point half covering the exhaust port, during which time the crank has advanced to 225 degrees of revolution, the working piston has completed its downward stroke and begun its return, practically 65 meeting the secondary piston. Before actual contact of the two pistons has taken place, however, the secondary piston has been caused to begin its return stroke at an accelerated velocity, so as to reach its high- 70 est point decidedly in advance of the working piston.

The cylinder head of the motor is pro- 75 vided with a typical spring seated inlet valve for the explosive mixture, which valve is caused to open as a result of the atmospheric rarefaction taking place on the downward stroke of the secondary piston, thereby admitting the said mixture into the cylinder in the space between the cylinder 80 head and the said secondary piston. This piston is provided with one or more spring seated valves, the opening of which is caused at the beginning of the return stroke of said piston thereby permitting the transfer of 85 the mixture from above the secondary piston to the space between the two pistons. It will thus be observed that a positive ejec- 90 tion of the exploded gases will have taken place before the fresh charge is admitted 95 between the two pistons, thereby eliminating any possibility of an affected mixture. During the return stroke of the two pistons, it is evident that an equilibrium of compres- 100 sion will exist between the same and be- 105 tween the secondary piston and cylinder head, so that the secondary piston is brought to a state of rest at top stroke under com- pression and without jar.

For a fuller understanding of the details 110 of my invention, I now refer to the sheet of drawing, in which A is the motor or engine

cylinder, having outer and inner walls 1 and 2, with an annular water circulating chamber 3 therebetween. Properly positioned in said walls 1 and 2, is formed a boss 4, the interior of which is cored out to provide an exhaust port 5, having a threaded opening 6, to which the usual exhaust pipe or muffler (not shown) may be attached. Near the lower extremity of cylinder A, is 10 provided a threaded opening 7, for ingress of a cooling medium to the annular chamber 3, and, at the upper end of the wall 1 is provided a similar opening 30 for the egress of said cooling medium, while a short distance 15 from the upper end of said cylinder is formed a pocket 8, communicating with the interior of the same, for the reception of a spark plug 9, which plug is connected by wires 10 and 10^a to suitable timing mechanism not shown. The lower end of cylinder A is fastened to a base or crank case B, which crank case is provided on its side outer walls 13, with the usual journal boxes or main bearings 15 and 15^a, Fig. 4, for the 20 rotation of a crank shaft 10. The cylinder A is preferably formed integrally with the cylinder head C and the inlet valve hollow protuberance 33^a, there being a water chamber 16 in said head communicating with the water chamber 3 aforesaid. The inlet 25 valve protuberance 33^a is generally placed centrally of the head C for neatness of construction and is provided with a spring seated inlet valve 34, located on the under or inner side of said head, there being a 30 valve stem 34^a extending through the protuberance 33^a to the exterior thereof, where said stem is embraced and acted upon by a helical spring 34^b, tending to maintain said inlet valve 34 in closed disposition against the under or inner side of said cylinder head C. Said protuberance 33^a has an outlet 35 therefrom, to which the usual type of carburetor (not shown) may be attached 40 by suitable fittings.

Within the wall 2 of the cylinder A and adjacent the inner face thereof, at points diametrically opposite each other, and extending the entire length thereof from the 45 lower edge of said cylinder to points adjacent the underside of the head C are machine finished holes 40 of preferably circular cross section, and there are produced grooves 41, connecting said holes with the 50 interior of the cylinder for its entire length, the resultants being a pair of longitudinal grooves diametrically opposite each other, sunk, as it were, in the face of said cylinder, terminating at and extending through 55 its lower edge, and parallel to its axis. These grooves are technically termed undercut or dovetailed grooves, inasmuch as their width is narrower at the surface than at other points in the depth thereof. It may 60 here be explained that the grooves 41 and

holes 40 are accurately machined and finely finished and are adapted for the free reciprocation therein of so called parallel rods 42, Figs. 5 and 6, the upper ends of which rods are fixed to a scavenger piston 43 reciprocating in the upper portion of the cylinder A as hereinafter more fully described. Before the cylinders A just referred to are ground internally to render the bores thereof essentially accurate, the 70 rods 42 are placed within the grooves 41, and holes 40, in order that the faces of their ribs 42^a may be ground simultaneously with the bore so as to coincide precisely with the contour and accuracy of the bores, in an 75 obvious manner.

It is now to be mentioned that when a cylinder is bolted to the base or crank case B, the said grooves are truly perpendicular to the axis of the crank shaft 10, and it is 80 further pointed out that a continuation of said grooves is formed in the opposite walls 13 of said crank case, and that these grooves extend downwardly to practically the horizontal axis of said case, which axis is coincident with the axis of the crank shaft 10.

Crank shaft 10 is what is known as a built up crank shaft and comprises two like disks 43^a in spaced apart relationship fixed to the shafts 10^a and 10^b and being connected together in said spaced apart disposition by a crank pin 44, in a manner common to this type of shafts. Embracing the crank pin 44 is the crank end 45 of a connecting rod 46, the opposite end of which is in 100 oscillable connection with a working piston 47 of the well known trunk or analogous type, which piston is arranged for reciprocation in the lower portion of the cylinder A.

In the outer faces of the crank disks 43^a are produced endless grooves 102, 103, and 104, forming what is technically known as face or raceway cams, which cams 50 are so constructed as to create a greatly accelerated 110 downward movement of the scavenging piston long after the beginning of the downward stroke of the working piston and to return said scavenging piston upon its upward stroke to its highest point in advance 115 of the completion of the upstroke of the working piston. The groove of the cam 50 at its largest curvature is concentric to the axis of crank shaft 10 and extends through an arc of 180 degrees, of which 45 degrees 120 extend beyond the crank pin from a radial line passing through said crank pin and said crank shaft, in the direction of rotation of the crank shaft, and, the ends of the said groove are rounded and connected by a 125. groove of a very flat curve. Adapted for engagement in said race way cams are anti-friction rollers 52 rotatably mounted at the side of the parallel rods 42, adjacent the faces of the disks 43^a in which are formed 130

the race way cams 50. On the inner or adjacent faces of the disks 43^a at points opposed to the race way cams, said disks have cut away, lightened portions 53 to compensate for the metal removed in producing the cams, so that said disks are in mechanical running balance, a matter readily comprehended.

The scavenging piston 43 is hollow in construction for purposes of lightness and has through the same an axial circular opening 54, surrounded by an annular wall 55, and on the underside of said piston, surrounding said opening is located a seating for a valve 56, the closing of which is induced by a helical spring 57, whereby said valve will only open against pressure behind piston 43.

The operation of my motor may be now explained as follows, it being assumed that the clearance space 100, Fig. 1, is filled with compressed gases and an explosion has taken place. The crank shaft, impelled by the trunk piston 47 and connecting rod 46 will rotate in the direction of the arrow pointer 101, but the scavenging piston 43 will remain quiescent due to the control of the concentric portion 102 of the cam 50, over the movements of the parallel rods 42. But as the crank pin passes through the first 135 degrees of the rotation the groove 104 governs the said rods, and in the next 90 degrees of crank travel, the scavenging piston descends at practically twice the speed of the working piston, so that at 225 degrees of the revolution both pistons are in theoretical contact thereby effectually ejecting the spent gases through exhaust port 5. As the scavenging piston descends, the inlet valve 34 opens, due to a partial vacuum, and admits a fresh charge of the explosive mixture into the space in the cylinder between the cylinder head C and the said scavenging piston. The latter at the termination of 225 degrees of revolution passes under control of groove 103 and in the next 90 degrees said piston is returned to its original position and is again influenced by the groove 102 as in Fig. 1. During the upward travel of the scavenging piston, the fresh mixture is transferred through valve 56 therein into the space between pistons 43 and 47, in

which space said mixture is compressed by the piston 47.

I have hereinbefore disclosed the preferred mode of practising my invention, but I reserve the right to make such and any changes as might occur to one skilled in the art to which this invention appertains, or to make any and all such alterations as might be permitted under the doctrine of equivalents.

Having thus fully described my invention I claim as new, and desire to secure to myself by Letters Patent of the United States:—

1. In an engine, a cylinder, pistons therein and a crank shaft, a connecting rod connecting one of said pistons, and said crank shaft, there being longitudinal grooves in said cylinder contiguous the bore thereof, rods located in said grooves fixed to the other of said pistons, and means in connection with said crank shaft, adapted to reciprocate said rods.

2. In an engine, a cylinder, pistons therein and a crank shaft, a connecting rod connecting one of said pistons and said crank shaft, there being undercut, longitudinal grooves in said cylinder contiguous the bore thereof, rods located in said grooves, their outer edges being flush with said bore, fixed to the other of said pistons, and means in connection with said crank shaft adapted to reciprocate said rods.

3. In an engine, a cylinder, pistons therein, and a crank shaft, possessed of disk like cheeks, and race way cams located in said cheeks, a connecting rod connecting one of said pistons and said crank shaft, there being longitudinal grooves in said cylinder contiguous the bore thereof, rods located in said grooves, fixed to the other of said pistons, and means on said rods engaging said race ways.

In testimony that I claim the foregoing as my invention, I have hereunto set my hand in the presence of two subscribing witnesses.

GEORGE WASHINGTON JONES.
